(57) **CLAIM**

The ornamental design for an automobile body, as shown and described.

DESCRIPTION

FIG. 1 is a top, front and right side perspective view of an automobile body showing our new design;

FIG. 2 is a top, rear and left side perspective view thereof;

FIG. 3 is a right side elevation view thereof;

FIG. 4 is a left side elevation view thereof;

FIG. 5 is a front elevation view thereof;

FIG. 6 is a rear elevation view thereof; and,

FIG. 7 is a top plan view thereof.

The wheels shown in broken lines throughout the drawings views are for environmental and illustrative purposes and form no part of the claimed design.
